UNITED STATES PATENT OFFICE.

WILLIAM S. ELLIOTT, OF PITTSBURGH, PENNSYLVANIA.

BAROMETRIC CONDENSER.

Application filed October 3, 1919. Serial No. 328,319.

To all whom it may concern:

Be it known that I, WILLIAM S. ELLIOTT, a citizen of the United States, residing at Pittsburgh, in the county of Allegheny and

5 State of Pennsylvania, have invented a new and useful Improvement in Barometric Condensers, of which the following is a full, clear, and exact description, reference being had to the accompanying drawing, forming part of this specification, in which the figure is a sectional elevation, largely conventional, of a barometric condenser embodying my invention.

10 My invention has relation to barometric condensers and is designed to provide a condenser structure capable of being used in connection with large engine installations, and in which the parts are so arranged as to greatly simplify the supporting structure 20 and provide a balanced or symmetrical construction. In large turbine installations, the exhaust pipes become large and bulky and the condensers are very heavy. The usual method of installation is to provide 25 an elbow at the top of the exhaust pipe which goes into the side of the condenser. This makes the condenser hang out at one side of the exhaust pipe, giving an unbalanced or unstable apparatus, and a tower 30 or other supporting structure is necessary in connection therewith.

In accordance with my invention I arrange the exhaust pipe 2 which carries the exhaust steam from the engine to the condenser in a centrally vertical position, and provide at the upper end thereof a T-connection 3 to each arm of which is attached a depending condenser structure 4. These condenser structures may be of any suitable 40 or usual character, this forming no part of my invention. Each structure is provided with a separate downwardly extending tail pipe 5 leading downwardly into a well 6. 7 designates a branched water supply pipe, one branch leading to each condenser.

45 The tail pipe 5 may be provided with any suitable supports 8, thus giving the condenser structure as a whole a three-point or multiple support.

50 It will be noted from the drawing that the entire structure is so arranged that the center of gravity of the structure as a whole comes within the base of the exhaust pipe, 55 the structure being arranged symmetrically

around the vertical center of such pipe. This gives a very stable arrangement which renders the use of towers or other extraneous supporting means unnecessary.

While in the accompanying drawing I 60 have shown only two condensers, it will be apparent that more than two condensers can be arranged symmetrically around the exhaust pipe.

I claim:

65 1. A condenser, comprising a centrally arranged exhaust pipe and a plurality of barometric condensers arranged around said pipe and connected therewith, said exhaust pipe forming the main support for said 70 condensers, substantially as described.

2. A condenser structure, comprising a centrally arranged exhaust pipe and a plurality of condensers arranged laterally of said pipe and connected with the upper portion thereof, the center of gravity of the structure as a whole coming within the base of said pipe, and said pipe forming the main support for said condensers, substantially as described. 80

3. A condenser structure, comprising a centrally arranged exhaust pipe and a plurality of condensers connected thereto and arranged substantially symmetrical with respect to the vertical axis of said pipe, said 85 exhaust pipe forming the main support for said condensers, each of said condensers having a depending tail pipe and a support for each of the tail pipes, substantially as described. 90

4. A condenser structure, comprising a centrally arranged exhaust pipe, and a plurality of condensers connected with the upper portion thereof and arranged substantially symmetrical with respect to the vertical axis of said pipe, said exhaust pipe forming the main support for said condensers, each of said condensers having an auxiliary point of support independent of said pipe, substantially as described. 95

5. A condenser, comprising a centrally arranged exhaust pipe and a plurality of condensers arranged around said pipe and connected thereto, said exhaust pipe forming the main support for said condensers, substantially as described. 105

In testimony whereof, I have hereunto set my hand.

WILLIAM S. ELLIOTT.
